GATE FOR SWINGING BRIDGE APPROACHES.

No. 434,932.

Patented Aug. 26, 1890.

UNITED STATES PATENT OFFICE.

GEORGE BENJAMIN HOWLAND, OF PONTIAC, ILLINOIS.

GATE FOR SWINGING-BRIDGE APPROACHES.

SPECIFICATION forming part of Letters Patent No. 434,932, dated August 26, 1890.

Application filed December 18, 1889. Serial No. 334,152. (No model.)

To all whom it may concern:

Be it known that I, GEORGE BENJAMIN HOWLAND, of Pontiac, Livingston county, Illinois, have invented certain new and useful Improvements in Gates for Swinging-Bridge Approaches, of which the following is a full, clear, and exact description, reference being had to the accompanying drawings and to the letters of reference marked thereon.

10 The object of my invention is to provide a simple and perfect gate which will automatically close the approaches of a swinging bridge when the bridge is swung open, and which is lifted up out of the way when the 15 bridge is closed, substantially as hereinafter fully described and as illustrated in the drawings, in which—

Figure is a side elevation of a swinging bridge with my improved gate guarding the 20 approaches thereof. Fig. 2 is plan view of the same. Fig. 3 is an elevation of the gate looking toward the bridge, and Fig. 4 shows a plan view of a modified detail of the same.

Referring to the drawings, A represents a 25 swinging bridge, and B B the approaches thereof. Secured to the upper ends, preferably the end posts or uprights of the bridge, are brackets a a, which project outward and upward in a parallel plane with the sides of 30 the bridge. Secured to the upper ends of the bracket on the same end of said bridge is a track C, which from each end pursues a horizontal course to a common point farther back on the bridge at its transverse center, thus 35 looking at the bridge from above, producing a V-shaped track on each end of the bridge.

b b represent, respectively, pairs of parallel vertical uprights, one pair being located on each side of the approach a short distance 40 back from the abutments of the same. These uprights support the transverse head-frame c, which bridges over the road-bed, and which at its center of length has projecting longitudinally and centrally toward and over the 45 bridge and slightly beyond the vertex of the V-tracks C the arm D. The arm D consists of two horizontal flat tracks d' d', one immediately above the other, which are united at their outer ends and suitably secured at 50 their inner ends to frame c. Both the upper and lower tracks have corresponding central

coterminous longitudinal slots e in them, as shown, and between the tracks is placed a block E, which is of a suitable thickness and breadth to permit it to move longitudinally 55 between the tracks freely. In order to prevent any lateral displacement thereof, I provide said block, preferably at or near both ends, with vertical studs f and g, respectively, which pass vertically through the block and 60 whose ends extend upward and downward therefrom through the slots of the tracks.

On the lower end of the stud f, below the arm D, is a traveler F, which as said bridge swings closed rolls against the inner vertical 65 surface of track C, and secured preferably to the lower end of stud g are two ropes G G, which run from said stud back to the under surface of head-frame c, where the right-hand rope G passes around a horizontal concave 70 pulley h, and the left-hand rope passes around a similar pulley. From these pulleys the rope passes laterally under head-frame c to about between the uprights b b, supporting the same, where, passing over vertical pulleys 75 k k, they pass vertically downward to and through the transverse horizontal bars K composing the gate. There may be one, two, or more of these bars, and they all are of such length that their ends pass between the up- 80 rights b b. The ropes are suitably secured to the lowest bar K, but pass through suitable openings in those above.

Secured to each pair of uprights b on a corresponding horizontal plane are the brackets 11, 85 which extend laterally outward from the side farthest from the road-bed, and upon which the ends of the lateral pins passing through top bar of the gate drop and rest when the gate has been sufficiently lowered. The intermediate bar is suspended from the top bar and the lowest bar of the gate is simply suspended by the ropes. The object of this construction of the gate is to enable the bars thereof to be picked up one after the other as the ropes are 90 drawn upward through the action of block E, as will be hereinafter more fully explained, so that the least possible space is occupied by the gate when lifted. I do not, however, wish to be considered as confining myself to a gate 95 constructed as described, for a gate having a number of transverse bars connected by ver-

tical boards or other devices would answer just as well.

The operation of my invention is substantially as follows: When the bridge is open, 5 the weight of the gate has caused it to lower, so as to close the approach, and has drawn the block E back between the tracks d d' until the stud g thereof reaches the limit of slots e farthest from the bridge. While in 10 this position, when the bridge is being swung closed from either direction, the end of the V-track C over the corner of the bridge leading toward the approach strikes the point of the circumference of traveler F farthest 15 from the bridge, and as said bridge continues to close, so as to come into proper alignment with the bridge-approaches, the obliquity of track C from the periphery described by its ends causes the block to move toward the 20 center of the bridge until the vertex of the track is reached, whereupon the bridge will be in the proper "closed" position for traffic over it, and the gates will be raised up high enough, so as not to obstruct the approaches.

25 As hereinbefore described, it would be necessary in order for the gates to be lifted ten feet for the block E to have a corresponding length of movement. This would necessitate a great length of the overhanging arm D. I 30 can avoid that, if desired, by connecting block E with one rope n to the lesser diameter of a stepped drum H, and then securing the ends of the ropes G so that the right-hand one as it winds thereon first touches the forward 35 point of the circumference of the greatest diameter of said drum and the left-hand rope G first touches the point diametrically opposite thereto. Now the unwinding of rope n, caused by block E being drawn toward the 40 center of the bridge, winds up ropes G faster, according to the increased diameter of the part of the drum it winds upon, (and with a given movement of the block,) than is possible were the drum all the same diameter (which, 45 however, I could use) or were the method hereinbefore described resorted to.

I wish to be understood as contemplating all structural changes which may be made as coming within the spirit of my invention.

50 What I claim is—

1. The combination, with a swinging bridge and the track C, each end of which, commencing at a point near the corner of the bridge, converges inward toward a common 55 point nearer the revolving center of the bridge, of the block E, ropes G G, gate K, and frame

for supporting and directing the course of the same, as set forth.

2. A swinging bridge and horizontal track C, each end of which, commencing at a point 60 near the corner at each end of the bridge, pursues a corresponding course to a common point nearer the revolving center of the same, in combination with block E, having a stud f and traveler F on the end thereof, ropes G G, 65 pulleys for directing ropes G G, gate suspended by said ropes, and frame for supporting the same, as set forth.

3. A swinging bridge and horizontal track C, each end of which, commencing at a point 70 near the corners of each end of the bridge, pursues a corresponding course to a common point nearer the revolving center of said bridge, in combination with uprights b, transverse head-frame c, arm D, consisting of two 75 tracks and projecting longitudinally toward the said bridge, as described, block E, moving between the tracks of arm D, ropes G G, pulleys for directing the course of said ropes, and gate K, as set forth.

4. A swinging bridge and horizontal track C, each end of which, commencing at a point near the corners of each end of the bridge, pursues a corresponding course to a common point near the revolving center of the same, 80 in combination with uprights b b, having the brackets 1, transverse frame c, arm D, consisting of two tracks and projecting therefrom horizontally toward the bridge, as set forth, block E, ropes G G, pulleys for directing 85 the course of said ropes, and a gate consisting of several bars, through the ends of which said ropes G pass, except the lowest, to which it is secured.

5. A swinging bridge and horizontal track 90 C, each end of which commences at a point near the corners of each end of said bridge and pursues a corresponding course to a common point located nearer the revolving center of the bridge, in combination with uprights b, 95 frame c, arm D, consisting of two tracks, each of which has corresponding coterminous longitudinal slots e therein, block E between said tracks and having studs f and g projecting therefrom through the slots thereof, ropes 100 G G, suitable pulleys for directing the course of said ropes, and a gate suspended on the ends of the latter, as set forth.

GEORGE BENJAMIN HOWLAND.
